UNITED STATES PATENT OFFICE.

HENRY HERMAN, OF NEW YORK, N. Y., ASSIGNOR, BY DIRECT AND MESNE ASSIGNMENTS, OF ONE-THIRD TO ETHEL HERMAN, ONE-THIRD TO MARY GENNIS, AND ONE-THIRD TO HARRY PORDY, ALL OF NEW YORK, N. Y.

BUTTON.

Application filed May 15, 1926. Serial No. 109,303.

This invention has reference to covered buttons and relates particularly to the furred species thereof.

One object of the invention is the production of an improved button of the character described, capable of being covered with fur-bearing skin, in a neat, efficient and expeditious manner.

Another object is to provide a button of the nature set forth, with means for tautly and uniformly stretching as well as firmly clamping the fur over and upon opposite sides thereof.

A further object is to produce a button of the type specified, embodying improved means whereby the same may be detachably secured to a garment or like primary support.

Still another object is the provision in a button of the class mentioned of an anchorage element which may be forced through the side of the garment without the necessity of preparatorily piercing the same.

A still further object is in providing a button of the kind referred to, with a lock releasably holding the anchorage element engageable with the garment.

A general object is to furnish a button and fastening of the genus alluded to, of practical and convenient construction; composed of few, simple and durable parts; not liable to get out of working order; readily applied or removed; besides, amenable to low cost of manufacture.

Other objects and advantages of the invention will become apparent as the specification proceeds.

With the aforesaid objects in view, the invention consists of the novel combinations and arrangements of parts hereinafter described in their preferred embodiments, pointed out in the subjoined claims, and illustrated on the annexed drawing, wherein like parts are designated by the same reference characters throughout the several views.

Generally described, the invention under consideration includes in its organization a mold over one face of which the covering material is stretched and having at the opposite side thereof a recess. A member provided with a dentated rim is adapted to have the latter forcibly retain the edges of the material in the aforementioned recess. Means formed with the retaining member

are capable of receiving an element piercing that part of a garment to which the button is affixed. Mechanism is supplied for detachably locking the piercing element to the receiving means on the retaining member. An anchorage flexibly connected to the piercing element serves to hold the same to the inner or reverse side of the garment.

The advantages of the invention as here outlined are best realized when all of its features and instrumentalities are combined in the one and same structure, but, useful devices may be produced embodying less than the whole.

It will be obvious to those skilled in the art to which the invention appertains, upon becoming conversant with the details thereof, that the same may be incorporated in several different constructions. The accompanying drawing, therefore, is submitted merely as showing the preferred exemplification of the invention.

In the said drawing which illustrates the invention in about twice natural size:

Fig. I is a front elevation of this improved button, parts thereof being broken away and other parts shown in section;

Fig. II is a bottom plan view of the construction shown in the preceding figure, that is, looking upwardly from the underside thereof, parts being shown in section and other parts omitted;

Fig. III is a side elevation of an element appearing in Fig. I, detached therefrom, looking at the same from the right towards the left of the view last named;

Fig. IV is a section taken on the line IV—IV of Fig. III, looking in the direction pointed out by the thereto appertaining arrows; and

Fig. V is a fragmentary sectional elevation, showing a modified form of the invention.

Referring now to these views for a detailed description of this improved button, the numeral "11" denotes the convex crown or outer surface of a form or mold 13, having an annular substantially flat face 15, at the under or opposite side thereof. Adjacent to the inner portion of said face 15, is located a recess 17, which may be formed by undercutting or bevelling the circumferential wall 19 pertaining to a head or extension 21. The latter has a face 23 offset from that of

the first mentioned annular face 15, in the manner of an outwardly projecting ledge. From the last named face 23 extends inwardly of the ledge-like head 21, a certain depth into the middle part of the mold or form 13, a pocket 25, which for convenience may be bored thereinto. Notwithstanding, that in the present exemplification of the invention, the said mold and the therewith 10 conjoined head 21, is represented as being circular in outline, it will be understood, that the same may have any other or approved configuration.

Upon the crowned surface 11 of the mold 13, is stretched the covering material A, which in the present instance is composed of a fur-bearing skin, the hairs whereof are indicated at B. This skin is drawn over the rounded outer corners formed between the said crown 11 and the intermediate face 15, and thence up against and around the circumferential wall 19 of the head 23. The means for holding or pressing the edge of the skin or material A into the recess 17, 25 comprises in its preferred embodiment, dentations or prongs 27, provided about the marginal portion of a disc-shaped retaining member 29. As shown, the inner or underside of this member is in juxtaposed relation of the outer face 23 of the head 21. The crimping or forcing together of the prongs 27, from their flat condition depicted at 27^a, Fig. II, around the free edge of the skin A, serves not only to draw the latter 30 taut, but also to firmly clasp it against the wall 19, wherewith the dentated rim of the retainer member coacts.

The central portion of the said member 29 is raised or bulged outwardly so as to constitute a neck 31 and therewith conjoined shoulder 33, the latter having an elongated aperture 35 therein, which as shown may be composed of one larger central hole and two smaller side perforations communicating therewith. In proximity to the basal part of said neck 31, are formed oppositely disposed arcuate slots 37, approximately quadrantal in shape. The purpose of these slots and of the aforementioned aperture 35, 45 will presently be described. Movable taking over the before named neck and shoulder, are the corresponding inner side and end walls 39, 41, respectively, of a cap 43. Concentrically of the latter, is an orifice 45, 50 which has also an extended shape and is of substantially the same size as the aperture 35, being capable of registering therewith. Ears or keepers 47 projecting in counter directions from the edges of the cap's side wall 39, are adapted when bent inwardly, 55 to enter the neck 31 through its slots 37. The ears referred to, cooperate with the said slots, both to maintain the cap 43 in its assigned position against the member 29, 60 as well as to limit the rotative movement of

the cap relatively to the neck 31 and its apertured shoulder 33. At 49, Fig. I, is represented that the exterior face of the side wall 39 of the cap, is fluted or roughened in order to afford a firm grip for the 70 operator's fingers when turning the said cap from one position to another, that is, to place the orifice 45 in register with the aperture 35, or else, in right angular relation thereto, as indicated by the full and dotted 75 lines in the middle part of Fig. II.

The means for securing the skin covered mold 11 to a garment C, such as a fur-coat, cloak or the like, comprises, as illustrated to best advantage in Figs. I and III, an element 51, flexibly connected to an anchorage 53, which may be in the nature of a washer, made of fibre or other suitable substance, appropriately colored to match the inside or the lining of the garment which it is intended to overlie. Said element 51 is loosely hinged to a pintle 55 forming part of a bail-shaped wire 57 that is seated within an opening 59 wherewith the washer 53 is centrally provided. The terminals of the 80 wire comprising said bail 57 are made to penetrate the body of the said washer and are clinched thereover, in the manner suggested at 61, Fig. 1. The free extremity of the element 51 which is preferably pointed 85 and sharp-edged, has also been given the formation of an arrow head 63, affording square shouldered abutments 65 thereunder, which as shown are slightly thinner than the shank of the element. It will thus be 90 perceived, that it is an easy matter to pierce the side C of a fur-garment, simply by forcing the pointed head 63 through the same. From the foregoing it will be seen that the 95 said element 51 has the dual function of an 100 anchorage as well as a piercer.

After the head 63 of the anchorage element has been passed through the side of the garment whereto the furred button is 105 going to be attached, the aforesaid head is 110 entered by way of the previously aligned aperture 35 and orifice 45, into the interior of the hollow neck 31 and the thereto adjacent pocket 25. Subsequent turning or rotating of the cap 43 into the position which 115 the parts are represented as occupying in Fig. II, disaligns the orifice 45 relative to the aperture 35. The anchoring element 51 is thereby effectively locked to the retaining member 29 and precluded from withdrawal, 120 by virtue of the reason that the egress of the abutments 63 being blocked, until registration of the said locking passages 35, 45, is again reestablished. Friction intermediate the contacting surfaces of the cap and 125 its keepers 47 with the shouldered neck 31, is sufficient to maintain the parts in the position wherein they are placed. The jointed connection of the said element with the anchorage washer 53, as well as the relatively 130

loose fit of the element's shank portion within the before named passages in the end wall 41 and the shoulder 33, affords the button sufficient flexibility to adjust itself to various stresses applied thereto from different directions, still without the garment being subjected to undue strains.

In the modification of the invention disclosed by Fig. V, the parts substantially the 10 equivalent of those already described, are designated by the same reference characters to which letter exponents are suffixed. Thus 13^a is the mold, A¹ the skin stretched thereover, and 23^a the underface of the mold, 15 which in this instance is situated at the same plane or level as the outer annular face 15^a, being separated therefrom by the recess 17^a, shown in this exemplification of the invention as being inclined in an outward direction, instead of inwardly, as in the first mentioned case. The dentated rim 27^b of the retaining member 29^a serves to force the skin or material A¹ into the said recess 17^a, the outward inclination of the latter acting also 25 to prevent retraction of the retainer from the mold 13^a, after it has once been driven in place. At 31^a is indicated a sleeve or bushing struck up from the central portion of the member 29^a and lodged within the 30 pocket 25^a. Internally this sleeve is threaded so as to receive the body of a screw 51^a constituting the piercing element proper, which in conformity with the previously described construction, is flexibly secured to the anchorage washer 53^a. Screwing up of the element 51^a will force its pointed end into contact with the bottom of the pocket 25^a sufficiently tight to hold the said element becoming loose or accidentally detached 35 from the retaining member.

At such times as the fur, covering either of the molds 11 or 11^a, becomes worn or soiled, it is an easy matter, with a sharp-pointed implement, to pry up the teeth 40 around the retaining member and remove the latter so that a new piece of skin can be substituted for an unsightly one. The retainer may thereupon be replaced and the teeth thereof re-used to secure or wedgingly 45 clasp the new fur-piece in its assigned position. Should these teeth after a few applications happen to break off, it is of no great expense to discard the old or broken retainer for a whole one, as the cost of the same is 50 comparatively low, on account of being capable of production by means of punch press operations. It is also relatively simple to

change the position of a button on the garment with which it is used. The holes pierced by one of the elements 51 or 51^a in 60 a garment are readily hidden by the surrounding hairs of the fur. From the foregoing it will be seen that the invention hereinabove set forth, provides an inexpensive and practical button which may be quickly 65 and neatly covered by the fur and that can also be firmly and expeditiously affixed to a garment.

While certain preferred embodiments of this device have been shown and described, 70 it will be understood that changes in the form, arrangements, proportions, sizes and details thereof may be made, without departing from the scope of the invention as defined by the appended claims. 75

Having described my invention what I desire to secure by Letters Patent and claim, is:—

1. A button including a form adapted to have a covering material laid over one of its 80 sides, said form having a recess in the other side thereof, a member acting to stretch the material around said form retaining the same in said recess, an element capable of being anchored by one extremity to a coacting garment, and means on said member serving to disconnectedly engage the free 85 end of said element.

2. In a button, a form including front and rear faces, a recess in the rear face of said form arranged in angular relation thereto co-extensively with its contour, said recess being disposed inwardly from the edges of said form, a covering for the said form overlying the front face of the same and having 90 portions extending over the recess, a plate juxtaposed on said rear face, prongs projecting from said plate at an angle coincident with the said recess and adapted to enter the latter over said portions, and means 95 for securing said plate to a support.

3. In a button, a form including front and rear faces, the rear face of said form having a recess disposed at an angle thereto being spaced inwardly from and coextensive with 100 the edge of the form, a plate corresponding substantially in size and shape with said recess, teeth projecting from the edge of said plate arranged to enter and conform to the angle of the said recess, and a cover 105 member for the said form having portions overlying the recess and capable of being held herein by said teeth.

HENRY HERMAN.
